CLAIM

The ornamental design for a bicycle cover, as shown and described.

DESCRIPTION

FIG. 1 is a perspective view of a first embodiment of a bicycle cover showing my new design;

FIG. 2 is a front elevational view thereof;

FIG. 3 is a rear elevational view thereof;

FIG. 4 is a top view thereof;

FIG. 5 is a bottom view thereof;

FIG. 6 is a right side elevational view with the left side being a mirror image thereof; and,

FIG. 7 is a perspective view of a second embodiment of a bicycle cover.

The broken line showing of the lock in FIG. 7 is for illustrative purposes only, merely disclosing the types of attachments which can be used, and forms no part of the claimed design. The undisclosed views of the second embodiment are identical in all respects to those of the first embodiment with the exception of the front wheel part of the cover.
